UNITED STATES PATENT OFFICE.

LEE G. LOYD, OF ARDMORE, OKLAHOMA.

STORAGE-BATTERY TOOL.

Application filed March 15, 1927. Serial No. 175,615.

This invention relates to storage battery tools and more particularly to a device for removing either the assembled covers and plates or the complete assembly of a storage 5 battery cell.

An important object of the invention is to provide a device of this character which enables a very firm grip to be taken upon the cell and which will permit removal of 10 the cell without the necessity of steaming or burning away the composition by means of which the cell is usually sealed.

A still further object of the invention is to provide a device of this character which, 15 if desired, may be employed as a handle for carrying the battery from place to place.

A further object of the invention is to provide a device of this character which may be readily applied to and removed from the 20 battery, which is simple in its construction and operation and which will be durable and efficient in service.

These and other objects I attain by the construction shown in the accompanying 25 drawings, wherein for the purpose of illustration is shown a preferred embodiment of my invention and wherein:—

Figure 1 is a sectional view showing a tool constructed in accordance with my invention 30 applied to a cell of the storage battery.

Figure 2 is a detailed sectional view through the plug of the tool showing the manner in which the shaft attachments coact therewith.

Figure 3 is a section on the line 3—3 of 35 Fig. 2.

Figure 4 is a bottom plan view of the plug detached.

Referring now more particularly to the 40 drawings, the numeral 10 generally designates the usual cell cover of a storage battery cell and 11 the threaded opening formed in these cells for the reception of the vent cap (not shown).

In accordance with my invention, I provide a metallic plug 12 having its lower end exteriorly threaded, as at 13, for engagement in the threaded opening 11 and its upper end provided with a head 14, the lower 45 surface of which is adapted to seat upon the upper surface of the cell cover about the threaded opening when the plug is fully inserted. The plug 12 has formed therein an axial bore 15 through which is directed a shaft 16. The lower end of the bore 15 is conical, as indicated at 17, and the shaft at

its lower end has a correspondingly shaped enlargement 18. The threaded section of the plug is longitudinally split at circumferentially spaced points, as indicated at 19. 60 The head 14 has in its upper surface a groove 19' extending diametrically thereof and upon the shaft 16 is secured a pair of diametrically opposed radially extending lugs 20 adapted to engage in the groove 19' 65 at opposite sides of the bore 15 and lock the shaft and plug against relative rotation. The upper end of the shaft 16 has a transversely extending handle 21 serving as a means whereby the shaft may be rotated, or 70 as a handle, by means of which the shaft and an article secured thereto may be transported.

In the use of the device, the usual plug of the cell having been removed, the plug 12 75 is substituted therefor and threaded thereinto by moving the shaft downwardly until the lugs 20 engage in the groove 19' and then rotating the shaft. The lugs 20 are so spaced from the lower end of the shaft 80 that this lower end is held above the plates of the battery and will not come in damaging contact therewith. When the plug 12 is screwed home, the shaft through the handle 21 may be employed to either withdraw 85 the cell in the cover of which the plug is inserted or to remove a portion of this assembly, as is desired. It is pointed out that when strain is placed upon the handle 21, the resistance to this strain will cause the 90 conical end of the shaft 18 to engage against the surface 17 of the bore and thus spread the threaded portion 13, so that this portion will fit tightly within the threads of the 95 battery cell and there is no danger of stripping these threads.

It will be obvious that the construction hereinbefore set forth is capable of a certain range of change and modification without departing from the spirit of my invention and I accordingly do not limit myself to such specific structure except as herein-after claimed.

I claim:—

1. In a storage battery tool, a plug having a threaded portion and adapted to replace the usual vent plug of a storage battery cell, a handle therefor and means operated by the application of strain to the handle for expanding the threaded portion 110 of the plug.

2. In a storage battery tool, a plug hav-

ing a threaded portion and adapted to replace the usual threaded vent plug of a storage battery cell, the plug having a bore, a handle embodying a portion extended through said bore, the threaded portion of the plug being longitudinally slotted and means upon said handle wedging into the bore of the plug at the threaded portion thereof upon the application of strain to the handle.

3. In a storage battery tool, a plug having a threaded portion and adapted to replace the usual threaded vent plug of a storage battery cell, the plug having a bore, a handle embodying a portion extended through said bore, the threaded portion of the plug being longitudinally slotted, means upon said handle wedging into the bore of the plug at the threaded portion thereof upon movement of the handle in one direction and means associated with said handle and engaging the plug upon movement of the handle in the opposite direction for preventing relative rotation of the plug and handle.

4. In a storage battery tool, a plug having a threaded portion and adapted to replace the usual threaded vent plug of a storage battery cell, the plug having an axial bore increasing in diameter toward its lower

end, the threaded portion of the plug being disposed at the lower end thereof and being longitudinally slotted, a shaft directed through the bore of the plug and having an upwardly tapering enlargement for coaction with the bore and a handle upon the upper end of the shaft.

5. In a storage battery tool, a plug having a threaded portion and adapted to replace the usual threaded vent plug of a storage battery cell, the plug having an axial bore increasing in diameter toward its lower end, the threaded portion of the plug being disposed at the lower end thereof and being longitudinally slotted, a shaft directed through the bore of the plug and having an upwardly tapering enlargement for coaction with the bore, a handle upon the upper end of the shaft, said plug having in the upper surface thereof a diametrically extending groove and means upon the shaft and engaging in said groove upon downward movement of the shaft through the plug for limiting such downward movement and for locking the plug and shaft against relative rotation.

In testimony whereof I hereunto affix my signature.

LEE G. LOYD.
